UNITED STATES PATENT OFFICE.

HOMER S. BERSLEY, OF COGGON, IOWA.

RAILWAY-CROSSING SIGNAL.

1,307,998.

Specification of Letters Patent. Patented June 24, 1919.

Application filed July 3, 1917. Serial No. 178,406.

To all whom it may concern:

Be it known that I, HOMER S. BERSLEY, a citizen of the United States, residing at Coggon, in the county of Linn and State of 5 Iowa, have invented certain new and useful Improvements in Railway-Crossing Signals, of which the following is a specification.

My invention relates to improvements in railway crossing signals, and it consists in 10 the constructions, combinations and arrangements herein described and claimed.

An object of my invention is to provide a railway signal including actuating means located at each crossing which is adapted to 15 be operated by a passing train at one crossing whereby suitable signals at an anterior crossing may be sounded and indicated to warn persons at the crossing of the approach of the train.

Another object of my invention is to provide a switch mechanism situated at a railway crossing with means adapted to be engaged by the wheels of a passing train whereby certain members of the switch 25 mechanisms are actuated to operate a luminous and an audible signal at an anterior crossing.

Another object of the invention is to provide a device of the class described having 30 duplicate switch mechanisms adapted to be operated by the wheels of the passing trains the switch mechanisms including inter-connections whereby signals at an anterior crossing may be indicated and the signals at a 35 posterior and previously indicated crossing may be simultaneously restored to an inoperative position.

Other objects and advantages will appear 40 from the following specification, reference being had to the accompanying drawings, in which:

Figure 1 is a longitudinal section illustrating the mechanism at two crossings the electrical signal mechanism being indicated 45 diagrammatically,

Fig. 2 is a plan view illustrating the arrangement of the mechanism adjacent to a rail, the web of the rail being shown in section,

Fig. 3 is an enlarged section of the mechanism shown at the right of Fig. 1, one of the pairs of switch contacts being shown in engagement as when the switch mechanism

of the posterior operating device is actuated, and

Fig. 4 is a vertical section on the line 4—4 of Fig. 3.

In carrying out my invention it will be observed that I locate a switch box 1 adjacent to one of the rails 2 of the railway. The switch box 1 is preferably metallic and is provided with the top 3 having a longitudinal opening or slot 4. One of the boxes 1 is sunk into the ground at each railway crossing a sufficient distance that the top 3 is disposed substantially the distance beneath the base of the rail 2 shown in Fig. 1.

A trip lever 5 is fulcrumed as at 6 within the box 1 and projects above the rail 2 as shown in Fig. 1 so that it may be engaged by the tread of a wheel 7 or by some other tripping means carried by a train. The trip lever 5 includes arcuate arms 8 and 9 which, together with the tripping lever 5, are movable in the slot in the top 3 and extend within the box 1 under normal conditions.

Actuating levers 10 and 11 respectively are fulcrumed as at 12 on either side of the trip lever 5. The upper end of each lever 10 and 11 is beveled as at 10^a and 11^a, respectively so that it may be readily engaged by the trip lever 5 when the latter is moved on the fulcrum 6 through the medium of the engagement therewith of the tread of the wheel 7. Contractile springs 13 are attached to the lower ends of the levers 10 and 11 and to a standard 14 mounted in the box 1. The springs 13 hold the levers 10 and 11 in a normally erect position.

A chain 15 connects the actuating lever 11 of one switch box 1 with the actuating lever 10 of a succeeding switch box 1. The chains pass over idlers 16 within the box 1 and over a second idler 17 in the bend of each of a pair of tubes 18 branching from the top 3. The trip lever 5 in moving toward the right causes the engagement therewith of the beveled portion 11^a of the lever 11 causing the lever 11 to move in a clockwise direction on its fulcrum 12. This results in the exertion of a pull on the chain 15 leading to the actuating lever 10 in the switch box 1 at the right of Fig. 1, causing said actuating lever 10 also to move in a clockwise direction until it reaches the position indicated in

dotted lines in Fig. 3.

The movement of the actuating lever 10 to the dotted line position shown in Fig. 3, permits the engagement of a movable contact 19 with a fixed contact 20 by the movement 5 of the supporting block of the movable contact, in a manner to be hereinafter described. A contractile spring 21 is connected between the lower end of each of the actuating levers 10 and 11 and the insulating block 22 on 10 which the movable contact 19 is mounted. The purpose of the contractile spring 21 is to normally draw the movable contact toward the companion lever and out of engagement with the fixed contact 20. The 15 springs 21 are smaller and weaker than the springs 13.

The engagement of the movable contact 19 with the fixed contact 20, releases a latch 23 normally disposed behind the insulated block 20 22, and the latch 23 moves upwardly behind the block 22 preventing the disengagement of the contact 19 with the contact 20 by the stored tension in the spring 21. The latch 23 is actuated by a spring 24 which is wound 25 about the stem 25. The latch 23, is mounted in suitable brackets 26 supported on the walls of the box 1.

A chain 27 connects to the lower end of the stem 25 of each latch 23 and with the 30 end of one of the arcuate arms 8 and 9. In Fig. 3, it will be observed that stem 25 of the latch 23 at the left, is connected through the medium of a chain 27 with the lower end of the arcuate arm 9. Similarly, the 35 stem 25 of the latch 23 at the right of the figure, is connected through the medium of a chain 27 with the lower end of the arcuate arm 8. Idler rollers 28 support and guide the chains 27.

40 When the trip lever 5 is moved on its fulcrum 6 toward the right, a pull is exerted on the right hand latch 23 through the medium of the chain 27. This pull will simply be spent on the spring 24 of the 45 latch 23 and will have no effect on the movable contact 19. The same movement of the trip lever 5 causes a pull to be exerted on the chain 27 connected with the lower end of the arcuate lever 9 which will result in moving 50 the latch 23 at the left of the figure downwardly. This pull will also be spent on the spring 24 and should the movable contact 19 be in engagement with the fixed contact 20, the tension stored in the retractile spring 55 21 will serve to separate the contacts 19 and 20 and break an electric circuit. Each of the movable contact supporting blocks 22 is provided with ribs 22^a which are slidable in grooves in a suitable guide way 29 as shown 60 in Fig. 4. The guide ways 29 and the insulating supports for the fixed contacts 20 are mounted on brackets 30 extending from the walls of the box 1. It should also be observed that the lower ends of the arcuate 65 portions 8 and 9 have connected thereto,

springs 31 which are jointed to the top 3. The springs 31 assist in returning the trip lever 5 to a normal position after it is acted upon by the moving wheel 7 of a train.

In order to prevent foreign matter from 70 entering the box 1 through the slot 4, a casing 1^a is built on top of the box 1 over the slot 4. The casing 1^a in turn has a slot 4^b in which the protruding end of the lever 5 moves. A slidable cover 4^c prevents dirt and 75 other substances getting into the casing 1^a. The cover 4^c is connected to the lever 5 in any suitable way, a pivot pin 4^d being indicated. It will readily be understood, of course, that as the lever 5 rocks to and fro on its fulcrum 6, the cover 4^c will simply slide on top of the casing 1^a and keep the slot 4^b covered at all times. The pivot pin 4^d on the sliding cover 4^c has a slot connection with the lever 5, this being necessary to compensate for the 80 arcuate movement of the trip lever 5 when it is moved, as previously explained.

Indicating devices consisting of an incandescent lamp 32 and an audible signal consisting of a bell 33, are located at each grade 90 crossing of the railway. Current for the operation of the signals 32 and 33 is derived from line wires 34. Branch connections 35 and 36 which are normally open, terminate at and are closable by the contacts 19 and 95 20. The closure of the electric circuit through the branch 35 upon engagement of the movable contact 19 with fixed contact 20, causes current from the line wires 34 to flow through the luminous signal 32 and the 100 audible signal 33 and issue a warning of the approach of the train at the grade crossing.

The operation of the device is as follows: The normal position of the parts is as indicated to the right in Fig. 1. At this time 105 the various contacts 19 and 20 which are identical in construction and operation in each instance, are separated. The wheels 7 or other tripping means of a train moving into engagement with the trip lever 5 causes 110 it to rock on its fulcrum 6.

This causes a pull on each of the chains 27 which accordingly causes the retraction of the respective latches 23. The movable contact 19 at the extreme left in Fig. 1 was 115 moved into engagement with the fixed contact 20 at a previous operation. The branch circuit 35 was thus closed and warnings through the medium of the signals 32 and 33 issued at the crossing.

The trip lever 5 in moving one side engages the upper beveled end 11^a of the actuating lever 11 causing the lever 11 to rock in a clockwise direction and exert a pull on the chain 15. This pull being transmitted to the 125 lever 10 in the box 1 at the right of Fig. 1, permits the engagement of the movable contact 19 with the fixed contact 20 so that a position of the parts is reached as indicated in Fig. 3. In this figure it will also be ob- 130

served that the pull on the chain 15 above referred to, causes the actuating lever 10 to be swung to the dotted line position whereby the lower end of the lever 10 will engage the 5 block 22 and slide this block to move the contact 19 into engagement with the contact 20 to close the circuit. The spring 21 under such condition may be sprung to one side intermediate its ends or it may be caught between the lever and block and force the block over by the push of the lever upon the spring. The spring 13 connected with the lower ends of the actuating lever 10 being more powerful than the spring 21 causes the 15 return of the lever 10 to its erect or normal position thus stretching the spring 21. The latch 23 in the meantime was forced upwardly by the spring 24 into the path of the insulating block 22 and prevents the disengagement of the contacts 19 and 20. The branch circuit 35 at the right of Fig. 1 is thus closed as shown in Fig. 1 and a warning is issued through the medium of the signals 32 and 33.

25 As previously stated, the engagement of the wheels 7 with the upper ends of the abutment lever 5, causes the exertion of a pull on the companion chain 27. This being the case at the left of Fig. 1, the respective latches 23 are retracted and since the latch 23 at the left is the only one holding the contact members 19 and 20 in engagement, it follows that the pull on the chain 27 causes the retraction of this latch and permits the disengagement 35 of the contact 19 with the contact 20 thus causing the discontinuation of the operation of the signals 32 and 33.

The same operation follows as the train approaches the successive grade crossings, it 40 being understood that as the wheels 7 of the train engage each trip lever, the signals of the anterior crossing are rendered operative, while the previously operated signals of the posterior grade crossings are rendered 45 inoperative.

While the construction and arrangements of the parts of the device, is that of a generally preferred form, obviously modifications and changes may be made without departing from the spirit of the invention or 50 the scope of the claims.

I claim:

1. A crossing signal including a switch box, a pivoted trip adapted to be rocked by 55 a movable abutment, a local circuit including an electric signal, terminal contacts of the local circuit adapted to be closed, means for latching the contacts into engagement, and means for unlatching the contacts upon 60 rocking the pivoted trip.

2. A crossing signal including a pair of switch boxes located at railway crossings, a pivoted trip in one box adapted to be rocked by a movable abutment, a local circuit 65 embracing an electric signal associated

with each box, terminal contacts in one box adapted to be closed, means for latching the contacts in closed position, terminal contacts in the other box, said contacts being separated, and means for simultaneously unlatching the contacts of one box, and closing the contacts of the other box upon rocking the trip lever of the first named box.

3. A crossing signal including a pair of switch boxes located at crossings, a pivoted trip adapted to be rocked by a movable abutment, a local circuit embracing an electric signal associated with each box, terminal contacts in one box adapted to be closed, a latch for retaining the contacts in engagement, terminal contacts in the other box normally opened, an actuating lever in said other box adapted to close the contacts, an actuating lever in the first named box adapted to be engaged by the pivoted trip, a flexible connection between said actuating levers, and a flexible connection between the latch of the first named box and the pivoted trip for simultaneously retracting the latch to separate the contacts of the first named box and operating the actuating lever of the second named box to close its contacts.

4. A crossing signal including a switch box below a rail, a pivoted trip in the box extending above the rail, an arcuate portion on the trip, a local circuit embracing an electric signal associated with the box, a fixed and a movable terminal contact for the circuit, said contacts adapted to be closed, an actuating lever adapted to close the contacts, a spring latch for holding the contacts closed, and a flexible connection between the arcuate portion of the trip lever and the latch for retacting the latch upon rocking of the pivoted trip.

5. A crossing signal including a switch box below a rail, a pivoted trip in the box extending above the rail, an arcuate portion on the trip, a local circuit embracing an electric signal associated with the box, a fixed and a movable terminal contact for the circuit, said contacts adapted to be closed, an actuating lever adapted to close the contacts, a spring latch for holding the contacts closed, a flexible connection between the arcuate portion of the trip lever and the latch for retracting the latch upon rocking of the pivoted trip, a second actuating lever in the box, and means for actuating and closing the contacts of an anterior switch box upon engagement with the last named actuating lever by the pivoted trip.

6. A crossing signal including a switch box, a pivoted trip in the switch box having a portion projecting above a rail, an arcuate arm on the trip having a spring connected with the box, a fixed contact and a movable contact, a local circuit embracing an electric signal terminating at said contacts, an actuating lever for moving said

- contacts into engagement, a retractile spring between the movable contact and said lever, a retractile spring for holding the lever in a normal position, a spring latch associated with the movable contact, and a flexible connection between the arcuate arm and the spring latch for retracting the latch upon movement of the pivoted trip in one direction.
10. 7. A crossing signal including a pair of switch boxes located at crossings, a pair of actuating levers pivoted in each switch box, means connecting a lever in one box with a lever in the remaining box, springs between the actuating levers for retaining them in erect position, fixed contacts and movable contacts in each box for the terminals of circuits, spring connections between the actuating levers and the movable contacts, spring latches co-acting with the movable contacts, a pivoted trip between each pair of actuating levers having a portion extending above the rail, arcuate arms on the trip having springs secured to the switch box, and flexible connections between the arcuate arms and the spring latches.
8. The combination of a switch box, a bracket arranged therein, a fixed contact including an insulating block, a guide way, a movable contact, an insulating block having a rib movable in the guide way, an actuating lever having spring connection with the insulating block of the movable contact, posteriorly actuated means for moving the contacts into engagement, a spring actuated latch for retaining the contacts in engagement, a pivoted trip adapted to be engaged by a movable abutment on the track, and connection therebetween and the spring latch for releasing the contacts.
9. A crossing signal including a pair of switch boxes, a movable trip in one box adapted to be moved by a movable abutment, a local circuit embracing an electric signal associated with each box, terminal contacts in one box adapted to be closed, terminal contacts in the other box, said contacts being normally separated, and means for simultaneously unlatching the contacts of one box and closing the contacts of the other box upon movement of the trip of the first named box.
10. A crossing signal including switch boxes, a movable trip, a local circuit embracing an electric signal associated with each box, terminal contacts in one box adapted to be closed, a latch for retaining the contacts in engagement, terminal contacts in the other box normally opened, an actuating lever in said other box adapted to close the contacts, an actuating lever in the first named box adapted to be engaged by the trip, a connection between said actuating levers, and a connection between the latch of the first named box and the movable trip, for simultaneously retracting the latch and separate the contacts of the first named box for operating the actuating lever of the second named box to close its contact.
11. A crossing signal including a switch box, a movable trip in the box, an arm carried on said trip, a local circuit embracing an electric signal and communicating with the box, a fixed and a movable terminal contact for the circuit, said contacts being adapted to be closed, an actuating lever adapted to close the contacts, a latch for holding the contacts closed, and a connection between the arm of the trip and the latch for retracting the latch upon movement of the trip.
12. A crossing signal including a switch box, a movable trip in the box, an arm on said trip, a local circuit including an electric signal associated with the box, fixed and movable terminal contacts in the circuit, said terminal contacts adapted to be closed, an actuating lever adapted to close the contacts, a spring latch for holding the contacts closed, a connection between the arm of the trip and the latch for retracting the latch upon movement of the trip, a second actuating lever in the box, and means for actuating and closing the contacts of an anterior switch box upon engagement with the last named actuating lever by the trip.
13. A crossing signal including a switch box, a movable trip in the switch box, an arm on the trip having a spring connected with the box, a fixed contact and a movable contact, a local circuit embracing an electric signal terminating at said contacts, an actuating lever for moving said contacts into engagement, a retractile coil spring between the movable contact and said lever, a retractile spring for holding the lever in one position, a spring latch associated with the movable contact, a connection between the arm and the spring latch for retracting the movable contact upon movement of the trip in one direction.
14. A crossing signal including a plurality of switch boxes, a pair of actuating levers pivoted in each box, means connecting the lever of one box with the lever of the remaining box, springs between the actuating levers for retaining the same in erect position, fixed contacts and movable contacts in each box for the terminals of circuits, spring connections between the actuating levers and the movable contacts, spring latches co-acting with the movable trip between each pair of actuating levers, an arm in the switch box having springs secured to the switch box, and connections between the arms and the spring latches.
15. The combination of a switch box, a bracket arranged therein, a fixed contact

including an insulating block, a guide way, a movable contact, an insulating block having a rib movable in the guide way, an actuating lever having spring connection with the insulating block of the movable contact, posteriorly actuated means for moving the contacts into engagement, a spring actuated latch for retaining the contacts in engagement, a movable trip, and connections

between the trip and the spring latch for 10 releasing the contact.

In testimony whereof I affix my signature in presence of two witnesses.

HOMER S. BERSLEY.
